UNITED STATES PATENT OFFICE.

WILLIAM B. FENN, OF WASHINGTON, PENNSYLVANIA.

DESIGN FOR A CRUET.

SPECIFICATION forming part of Design No. 36,876, dated April 12, 1904.

Application filed April 21, 1903. Serial No. 153,711. Term of patent 7 years.

To all whom it may concern:

Be it known that I, WILLIAM B. FENN, a citizen of the United States, residing at Washington, county of Washington, and State of Pennsylvania, have invented a certain new, original, and ornamental Design for a Cruet, of which the following is a specification.

My invention is shown in the accompanying drawing. Figure 1 is a side elevation of the cruet, the same being transparent and the

interior surface being indicated by dotted lines. Figure 2 is a bottom plan view of the same.

I claim, and desire to secure by Letters Patent, the ornamental design for a cruet as shown.

WILLIAM B. FENN.
